UNITED STATES PATENT OFFICE.

CHARLES M. TAYLOR, OF TORONTO, ONTARIO, CANADA.

BALLOT-BOX.

SPECIFICATION forming part of Letters Patent No. 398,911, dated March 5, 1889.

Application filed March 24, 1888. Serial No. 268,433. (No model.)

To all whom it may concern:

Be it known that I, CHARLES MILLARD TAYLOR, cutter, of the city of Toronto, in the county of York and Province of Ontario, have 5 invented certain new and useful Improvements in Ballot-Boxes; and I do hereby declare that the following is a full, clear, and exact description of the same.

My invention relates more particularly to 10 that class of ballot-boxes which are used in balloting for members in societies, clubs, and other organizations, and for similar purposes, and has for its object to enable the ballot to be quickly and accurately taken, with perfect 15 secrecy while the voting is progressing, and at the same time allow the result to be made manifest to the proper officers or to the whole membership when required without disturbing or changing the position of the balls, and 20 thus preventing all chance of fraud.

To this end my improvements consist, chiefly, in providing the ballot-box with a narrow chamber of just sufficient depth from back to front to receive the balls of both 25 colors in single rows, one above the other, such chamber having a transparent front covered by a flap or slide which may be thrown back and thus disclose at a glance the condition of the ballot. Means for emptying this 30 chamber and a receptacle for loose or spare balls are also included in my invention; but for full comprehension of the details of construction reference must be had to the accompanying drawings, forming part of this specification.

35 In said drawings letters of reference similar to those hereinafter mentioned designate like parts, and Figure 1 represents a transverse vertical section of a ballot-box constructed according to my invention; Fig. 2, a back view, and Fig. 3 a front view (on a reduced scale) with flap turned up and broken away.

The box proper is made up of two suitably-shaped side boards, A A, a bottom, B, a back board, C, extending up from the bottom only a short distance, a slanting top board, D, and a front, E, within which is set a pane of glass, F, or other transparent substance, such as 45 clear mica.

The mouth or funnel G is immediately under the top board, D, and has sides g g (shown in Fig. 2) separate from the sides of the box, being of reduced width, and its bottom g' is

slanted, preferably so as to be parallel with 55 the top of board.

II is the ball-chamber supplied through the mouth G. It is formed by the glass front F and a vertical back board, K, extending down from the end of the said mouth and 60 joining the sides A, its lower edge being about opposite to the lower edge of the glass. The bottom h of this ball-chamber is hinged to the front board, E, or a slide may be substituted, if desired, and when the box is ready 65 for balloting is kept closed by a suitable catch, k, in some such manner as shown in Figs. 1 and 2. The transparent front is covered by a hinged flap, L, or a slide or curtain may be used, if desired, until the result of 70 the ballot is to be ascertained, when by throwing this covering back the number of black balls deposited can be immediately seen dispersed among the white, as indicated in Fig. 3. The loose or spare balls can be ac- 75 commodated in the tray formed by the bottom B and front and back boards; or a drawer may be used, if preferred.

In the ballot-box above described the catch of the hinged bottom of the ball-chamber is 80 released when the balloting is finished, and the balls in said chamber immediately fall into the tray or drawer below.

I do not limit myself to the exact construction and arrangement above described, and 85 shown in the drawings, as many variations may be adopted without departing from the essential features of my invention.

What I claim, and desire to secure by Letters Patent, is as follows:

1. In a ballot-box, the combination, with a suitable case having an inlet for the balls, of a ball-chamber in communication with said inlet and having a transparent face, a removable covering for said face, and a hinged or 95 removable bottom for said ball-chamber, substantially as and for the purpose specified.

2. In a ballot-box, the combination, with the case, of the glass front F, flap L, mouth or funnel G, ball chamber II, hinged bottom 100 h, and catch k, substantially as and for the purpose set forth.

Toronto, Ontario, December 23, 1887.

C. M. TAYLOR.
